M. M. KOHN,
UNIVERSAL HOLDING BRACKET FOR POWER UNITS.
APPLICATION FILED APR. 20, 1918.

UNITED STATES PATENT OFFICE.

MILTON M. KOHN, OF NEW YORK, N. Y., ASSIGNOR TO THE VENTILATOR FAN CO., INC., OF NEW YORK, N. Y., A CORPORATION OF NEW YORK.

UNIVERSAL HOLDING-BRACKET FOR POWER UNITS.

1,307,011.

Specification of Letters Patent. Patented June 17, 1919.

Application filed April 20, 1918. Serial No. 229,872.

To all whom it may concern:

Be it known that I, MILTON M. KOHN, a citizen of the United States, residing in borough of Manhattan, in the county of 5 New York and State of New York, have invented certain new and useful Improvements in Universal Holding-Brackets for Power Units, of which the following is a specification.

10 My present invention relates to a universal holding bracket for holding in operative position certain desired forms of power units such as electric motors and the like.

Another object of the present invention is 15 to provide in such universal bracket a suitable frictionless bearing whereby the power unit grasped therein may be provided with an additional bearing, forming, substantially, a foot-step bearing for such motors 20 when the device is operated in a vertical position.

Another object of the invention is to provide such adjustable motor holding means with a simple and efficient means of adjustment and lock for all adjusted positions.

25 A further object of the invention is to provide means on the said device whereby any standard type of electric motor may, within limits, be firmly held between the 30 grasping means without it being necessary to provide the housings or other parts of such standard motors with a special coöperating gripping means. On the other hand, where it is deemed advisable, coöperating 35 gripping devices may be provided upon the said motors.

Another object of the invention is to provide means on said gripping device of an extremely simple nature whereby the gripping holder may be readily and adjustably applied to any form of base or other supporting means so that such means will be universally adaptable.

These and other features, capabilities, and 45 advantages of the invention will appear from the subjoined detail description of certain specific embodiments thereof, in which—

50 Figure 1 is an elevation partly in section of one embodiment showing a motor anchored thereto.

Fig. 2 is a small section substantially on the line 2—2 of Fig. 1.

55 Fig. 3 is an elevation of another embodiment in which the fingers have plain surfaces.

Figs. 4 and 5 are fragmental sectional views showing still other modifications of fingers.

Fig. 6 is a fragmental section showing a modification of the connecting means between the supported member and the support. 60

In the embodiment illustrated in Fig. 1, the stem 10 is partially threaded at its upper half 11 and there is provided thereon 65 an adjustable locknut 12 which locks the threaded gripping or fulcrum nut 13. Just above this, there is also provided a pivot bracket 15 upon which is mounted the gripping arms 18, the said pivot bracket being 70 provided with its own locknut 14.

The bracket 15, when used for supporting a motor or the like, is provided with an annular recess or seat 16 at its free end, in the present instance the upper end, to receive 75 the thrust-bearing A of usual construction which acts as a foot-step bearing for the supported device, in which coöperates the shaft B of the motor M Fig. 1. Laterally extending from the bracket 15 are provided 80 the pivot lugs 17, for pivotally mounting the arms 18, the lugs being arranged in pairs to receive an arm 18 between them with a pivot pin 19 extending through a pair of lugs 17 and an arm 18. 85

There are provided preferably three such arms 18, spaced equidistant, each arm having a finger portion 19' which coöperates with the finger portions of the other arms and with the device to be supported, and 90 each arm having a fulcrum portion 20 to coöperate with the fulcrum nut 13. The finger portions 19 in the embodiment illustrated in Fig. 1, may have inner corrugated faces 21 to increase their grasping efficiency 95 and are shown engaging corrugated engaging plates C formed on the motor M. The lever arms 20 have inner fulcrum nut engaging faces 22 to engage the wedging face 23 of the fulcrum nut 13, preferably formed 100 conical as illustrated.

In operation, assuming that the bracket 15 has been set in place on the threaded portion 11, the locking nut 14 secured up thereagainst, the thrust-bearing A placed 105 in the seat 16 of the bracket 15, which adjustably supports the thrust-bearing A, the motor located with its shaft B disposed in the bearing A, and the corrugated plates C registering with the finger portions 19,—the 110

- fulcrum nut 13 is then screwed up with its wedging face 23 engaging the faces 22 of the lever arms 20 until the required tension is produced, whereupon the locking nut 12 5 is secured up against the fulcrum nut 13 and the support is ready for use.

The embodiment illustrated in Fig. 3, is substantially the same as that illustrated in Fig. 1, except that the finger portions 24 10 are provided with plain faces 25 instead of the corrugated faces such as the faces 21 of the finger portions 19.

In the embodiment illustrated in Fig. 4, a finger portion 26 is shown which has an 15 adjustable cone point 27 mounted therein for engaging the device to be supported.

In the embodiment illustrated in Fig. 5, a finger portion 28 is shown provided with a half round bore having a seat 29 for receiving the lower end of a screw 30 which engages the threads of a half round recess 31 formed in the device to be supported, and is anchored in position between the device to be supported and the finger portion 28 as 25 shown. With this arrangement, it is possible to adjust the alinement of the motor axis relative to the support axis without disturbing the tension of the supporting member.

30 In the embodiment illustrated in Fig. 6, the bracket 32 is not directly threaded to the threaded portion of the supporting member on stem 10, as is the case with the bracket 15 of the embodiment illustrated in Fig. 1. In 35 this embodiment, the bracket 32 is threaded onto an extension 33 formed on a cup 34 provided with a seat 35 for receiving the thrust-bearing 36, the extension 33 being threaded to the threaded portion 37 of the supporting member. By this arrangement, it will thus be possible to adjust the distance and bearing between the supported power unit and the supporting member without disturbing in any way the adjustment alinement, axial or otherwise, of the supporting 40 and supported members.

While I have not shown any means of supplying oil to the thrust bearing A, it is obvious that any well known means of supplying such lubrication may be employed.

As previously noted, in order to render my gripping device of extremely simple nature so that it may be readily and adjustably applied to a ceiling, desk, wall, or other desirable form of base, ornamental or otherwise, the lower portion of the support is arranged in a stem form as at 10, Fig. 1, said stem being either cylindrical or square. It is obvious that the various forms of bases 55 above referred to need only have a suitable bore to receive said stem into which it may be rigidly attached by any suitable fastening means of the customary type.

It is obvious that various changes and 60 modifications may be made to the details of

construction without departing from the spirit of my invention, or exceeding the scope of the claims.

I claim:

1. A holding bracket comprising, with a supported device, a supporting stem, a foot-step bearing for the supported device seated on said supporting stem, means for adjustably supporting the foot-step bearing on said stem, means pivotally connected to the supporting stem for grasping the supported device, and means for adjusting the tension of said grasping means. 70

2. A holding bracket comprising, with a supported device, a supporting stem, a bracket threaded on said stem and having an annular seat, an adjustable foot-step bearing for the supported device engaging said annular seat, arms for grasping the supported device between them, levers on said arms, and wedging means on said supporting stem disposed to coöperate with said levers to adjust the tension of said arms on the supported device. 80

3. A holding bracket comprising with a supported device, a supporting stem, a bracket threaded on said stem having a seat formed at the free end thereof, an adjustable foot-step bearing for the supported device engaging said seat, ears formed on said bracket, arms pivotally mounted in said ears for grasping the supported device, levers on said arms, and a wedging nut threaded on the supporting stem and coöoperating with said levers to adjust the tension of said grasping arms on the supported device. 90

4. A holding bracket comprising, with a supported device, a supporting stem, a bracket on the supporting stem having an annular seat formed at the free end thereof, a thrust bearing engaging said annular seat and forming a foot-step bearing for the supported device, arms pivotally connected to said bracket for grasping the supported device and having levers, and means coöperating with said levers for adjusting the tension of said arms on the supported device. 105

5. A holding bracket comprising, with a supported device having retaining means on the exterior thereof, a supporting stem, a bracket on the supporting stem having a seat at its free end, a foot-step bearing for the supported device engaging said seat, arms pivoted on the supporting stem for grasping the supported device and having retaining means for engaging the retaining means on the exterior of the supported device and having levers, and means coöperating with said levers for adjusting the tension of said arms on the supported device. 115

6. The combination with a supported device, of a support, a bracket on said support, a seat formed at the free end of said bracket for receiving said supported device, arms pivotally connected to said bracket, finger 120

portions on said arms, friction faces on said supported device and on said finger portions to coöperate with one another to increase the grasping efficiency of the finger portions, 5 and means for adjusting the tension of said finger portions on said supported device.

7. A holding bracket comprising, with a supported motor having an inclosing case and an extended shaft, a supporting stem, 10 an adjustable bracket on said supporting stem having a seat at its free end, a foot-step bearing disposed in said seat to receive the shaft of the motor, arms pivotally connected to said bracket for grasping the exterior of 15 the case of the motor, and means for adjusting the tension of said arms on the exterior of said motor case.

8. A holding bracket comprising, with a supported motor having an inclosing case 20 and an extended shaft, a supporting stem, a bracket on said supporting stem having a seat at its free end, a foot-step bearing disposed in said seat to receive the shaft of the motor, arms pivotally connected to said 25 bracket for grasping the exterior of the case of the motor, and means for adjusting the

tension of said arms on the exterior of said motor case.

9. A holding bracket comprising, with a supported motor, a supporting stem, an adjustable bracket on said supporting stem having a seat at its free end, a thrust-bearing disposed in said seat to receive the motor, arms pivotally connected to said bracket for grasping the motor, and means 35 for adjusting the tension of said arms. 36

10. A holding bracket comprising, with a motor having an inclosing case and an extended shaft, a supporting stem, an adjustable bracket on said supporting stem having 40 an annular seat at its free end, a thrust-bearing disposed in said annular seat to receive the shaft of the motor, arms pivotally connected to said bracket for grasping the exterior of the case of the motor, and means 45 for adjusting the tension of said arms on the exterior of the motor case. 46
